United States Patent Office.

FRANK OSBORNE, OF SOUTH HANSON, ASSIGNOR TO HIMSELF AND W. HERBERT KEENE, OF EAST BRIDGEWATER, MASSACHUSETTS.

Letters Patent No. 92,637, dated July 13, 1869.

IMPROVED INSTRUMENT FOR CUTTING PEGS FROM BOOTS, &c.

The Schedule referred to in these Letters Patent and making part of the same.

To all whom it may concern:

Be it known that I, FRANK OSBORNE, of South Hanson, in the county of Plymouth, and State of Massachusetts, have invented certain Improvements in Instruments for Cutting Pegs from Boots and Shoes, of which the following is a full, clear, and exact description, reference being had to the accompanying drawings, making part of this specification, in which—

Figure 1 is a perspective view of my improved instrument.

Figure 2 is a longitudinal section through the centre of the same.

Figure 3 is a transverse section, on the line $z z$ of fig. 2.

The device ordinarily used for cutting pegs from the interior of boots and shoes is objectionable, for the following reasons, viz: Not being surrounded with a guard, its knife-edges are apt to be brought against and injure the upper leather, and the form of the portion of the instrument adjacent to the knife-edges is such, that it becomes extremely difficult to sharpen them when dull and worn away, and the whole instrument soon becomes worthless, and is discarded for a new one.

My invention has for its object to remove the above-mentioned difficulties, and consists in a knife made independently of and removable at pleasure from the main portion of the instrument, by which construction, when the cutting-edge is dull, the knife may be readily removed to be sharpened, and when worn away may be replaced by a new one at a trifling cost.

To enable others skilled in the art to understand and use my invention, I will proceed to describe the manner in which I have carried it out.

In the said drawings—

A represents a circular metallic rod, provided at one end with a wooden handle, B.

At the opposite end of this rod is formed a screw-thread, a , which fits into a corresponding thread in the

inner end of a metallic socket or plate, C, which is slotted out, for the reception of a metallic block, D, which is held in place therein, and is pressed tightly against a thin blade, E, provided with cutting-edges, $b c$, on two of its opposite sides.

The outer extremity of the portion of the rod provided with a screw-thread fits into a recess in the centre of the rear end of the block D, by which construction the knife-blade may be held immovably in place, the slotted plate C serving as a frame or guard to enclose the knife-blade, and protect the "upper" from injury from its edges, $b c$.

On reference to fig. 2, it will be seen that the inclination of these cutting-edges $b c$ to the shank or rod is such, that in one position of the rod the edge b forms an acute angle therewith, to adapt it for use in cutting off the pegs projecting up into the interior of the boot or shoe at its shank and toe-portions, while, when the rod is turned over, the edge c makes an obtuse angle therewith, or inclines out therefrom, to adapt it for use in cutting off the pegs projecting up inside the sole at and near the heel.

Claims.

What I claim as my invention, and desire to secure by Letters Patent, is—

An instrument for cutting pegs from boots or shoes, provided with a removable knife, E, substantially as described.

Also, the slotted socket C, and block D, in combination with the knife E, and rod A, with its screw-thread a , operating substantially as described, for the purpose set forth.

FRANK OSBORNE.
